Primary Examiner — Mary Ann Calabrese*Assistant Examiner* — Katelin G Kloberg(74) Attorney, Agent, or Firm — Loza & Loza, LLP; Heidi L. Eisenhut(57) CLAIM

The ornamental design for a stake, as shown and described.

DESCRIPTION

FIG. 1 is a top, front, right side perspective view of a stake, showing my new design;

FIG. 2 is a right side elevation view of the stake of FIG. 1;

FIG. 3 is a left side elevation view of the stake of FIG. 1;

FIG. 4 is a front elevation view of the stake of FIG. 1;

FIG. 5 is a back elevation view of the stake of FIG. 1;

FIG. 6 is a top view of the stake of FIG. 1; and,

FIG. 7 is a bottom view of the stake of FIG. 1.

The broken lines depict environmental subject matter that forms no part of the claimed design.

1 Claim, 5 Drawing Sheets(56)
